UNITED STATES PATENT OFFICE.

ALFRED FORNANDER, OF NEW YORK, N. Y.

DEVICE FOR SHARPENING CUTTING INSTRUMENTS.

1,110,619.

Specification of Letters Patent. Patented Sept. 15, 1914.

Application filed July 2, 1912. Serial No. 707,190.

To all whom it may concern:

Be it known that I, ALFRED FORNANDER, a subject of the King of Sweden, residing in the borough of Manhattan, in the city, county, and State of New York, have invented new and useful Improvements in Devices for Sharpening Cutting Instruments, of which the following is a specification.

This invention relates to devices for sharpening cutting instruments, such as razor blades and surgical instruments, and it is the primary object of the invention to provide a device of this character which is simple and cheap in construction and efficient in operation.

A further object of the invention is to provide a device of this character which is in the nature of a combined honing and stropping device, and which by a simple manipulation may be adapted at will to use as either a honing or stropping device.

In carrying out the above object, I provide a pair of rotatable abrasive carrying members, which may be in the form of disks preferably of leather, said disks being face-butted and having axial movement. The blade to be sharpened is carried by a support projecting between the disks which also serves to separate the latter. To cause the disks to yieldingly engage with the sides of the cutting edge of the blade, I provide a pair of resilient fingers to engage with the outer surfaces of the disks, said fingers being carried by a rocker connected to and actuated by the disk rotating means whereby said fingers alternately engage with the disks and cause one of the disks to engage with one side of the cutting edge of the blade alternately with the engagement of the other disk with the opposite side of the cutting edge of the blade.

Another object of the invention relates to the providing of the disks with a plurality of different abrasive surfaces whereby to utilize the device for honing or stropping purposes, and to means to adjust the actuating means to cause different portions of said disks to engage with the blade.

In the drawings accompanying and forming a part of this specification Figure 1 is a side elevation illustrating an embodiment of my invention. Fig. 2 is an end elevation, illustrating in section a blade in operative engagement between the disks and showing the manner of sharpening the same. Fig. 3 is a perspective view of the supporting

standard for the disks. Fig. 4 is a perspective view of the rocker with the resilient disk engaging fingers. Fig. 5 is a face view of one of the disks. Fig. 6 is a perspective view of a bushing upon which the disks are mounted. Fig. 7 is a perspective view of the disk actuating means. Fig. 7^a is a perspective view of a supporting stud upon which the bushing and the disk actuating means are rotatably mounted. Fig. 8 is a perspective view of the means to connect the resilient finger rocker to the actuating means. Fig. 9 is a perspective view of one form of gage to regulate the distance to which the blade may be inserted between the disks, and which also serves to withdraw the blade from the disks. Fig. 9^a is a perspective view of a modification of the gage shown in Fig. 9. Fig. 10 is a sectional detail view of the means to adjustably connect the disk actuating means to the resilient finger rocker actuating means; and Fig. 11 is a perspective view of one of the clamping members to maintain the blade in its support.

Similar characters of reference designate like parts throughout the different views of the drawings.

In the drawings I have shown an embodiment of my invention comprising a base 12 having an upright standard 13. A pair of pliable and rotatable abrasive carrying members 14, 14', which may be in the form of face-butted disks preferably of leather 90 adapted to have axial movement relative to each other, are mounted on a bushing 15 (Fig. 6) passing through central apertures in the disks and rotatably mounted on a headed stud 16 screw threaded into the standard 13; said bushing provided with an annular flange 17 to lie adjacent to the outer side or surface of the disk 14. Also rotatably mounted on the bushing 15 is an annular member or disk 18 having a plurality of circumferentially disposed pins 19 projecting laterally therefrom and adapted to pass through perforations in the disks 14, 14' with their free ends abutting against the face of the bushing flange 17. The annular member 18, which is in the nature of an actuator for the disks, is provided with an operating crank 20 and operatively connected to the flange of the bushing by a pin or detent 21 carried in a housing or box 23 connected to said member and normally caused to engage with one of a pair of

apertures 22 in the flange 17 by a spring 24 (Fig. 10). It will be noted that the housing 23 for the pin 21 is of greater diameter than the pins 19, and the apertures in the 5 disks 14, 14' for the pin housing 23 are, therefore, of necessity of greater diameter than the apertures through which the pins 19 pass, said openings serving as a means to properly locate or adjust the abrading 10 disks relatively to each other when mounting said disks upon the pins 19 of member 18, for a purpose to be hereinafter described.

A support 26 for the instruments to be sharpened, (in the present instance shown 15 as a razor blade and designated in a general way by B, Fig. 2,) extends up from the base 12 to project between the abrading disks and also serves to separate said disks as they are rotated. A pair of spring clamping members 24, 24 engaging at opposite sides of the blade to maintain it in the support, are carried in longitudinal recesses or slots 25, 25, formed in the base of the support 26 with their free ends yieldingly maintained in engagement with the sides of the blade by means of a winged clamping bolt 27, and by means of which bolt the tension 20 with which the clamping members engage the blade is adjusted.

30 The abrading disks 14, 14' are adapted to be normally rotated in a direction indicated by the arrow in Fig 1, and should a blade to be sharpened be inserted between said disks to a point beyond a line assumed to 35 be drawn vertically through the axis of rotation of the disks, the disks as they are rotated would come against the cutting edge of the blade with the consequent cutting and destroying of the disks. Therefore, to prevent the insertion of the blade too far between the disks, I provide a gage 28 removably engaging in a groove in the top of the support 26 and having at its inner end laterally projecting flanges 29, which are in the 40 nature of strops against which the end of the blade abuts when inserted between the disks. The insertion of the gage itself between the disks is limited by a laterally projecting portion 30 which is in the nature of 45 a finger piece to insert and remove the same. This gage also serves as an auxiliary or interchangeable support for the blade, the back of the blade resting upon the gage, and by means of which the blade is withdrawn from between the disks.

50 As already stated, the device may be utilized either as a honing or a stropping device, and for this purpose the working faces of the sharpening or abrading disks 60 14, 14' are provided with different abrasive surfaces as shown in Fig. 5. In said Fig. 5 the lightly stippled surface S is adapted for stropping, and may or may not be provided with an abrasive material; that is, it may be oiled, or provided with oil and a very finely

communited or powdered abrasive material, such as powdered emery, carborundum and the like, while the heavily stippled portion of the disks, as H, is provided with a coarser abrasive material either of which by a simple manipulation of the actuating member 18 may be caused to engage at will with the blade. The blade support 26 projecting up between the sharpening disks separates them as they are rotated, and to cause the disks 70 to engage with the blade to sharpen the same, I provide means to engage with the outer surfaces of the abrasive disks to yieldingly press the same against the blade, the engagement of one disk, as 14, with one side 80 of the cutting edge of the blade being alternate with the engagement of the other disk, as 14', with the opposite side of the cutting edge of the blade. For this purpose the sharpening disks are so mounted that the 85 honing portion, or portion having the coarser abrasive, of one disk comes opposite the stropping portion of the other disk, and vice versa.

To cause the disks to alternately engage 90 with opposite sides of the cutting edge of the blade I provide a pusher, comprising a pair of preferably resilient fingers 31, 31' connected by screws to a rocker 32 rotatably mounted on a headed stud 33 screw threaded 95 into the blade support 26. The rocker 32 is actuated by means of an eccentric 34 formed on or connected to the rear of the flange 17 of the bushing 15, a strap 35 surrounding said eccentric and connected to the rocker 100 by a pitman or link 36 pivotally connected to an offset portion of the rocker by a screw 37 having a slotted head. As the abrading disks are rotated by the crank 20 for approximately 180 degrees of revolution the 105 finger 31 will be thrown into and out of engagement with and caused to yieldingly bear against, the outer side of the disk 14 and press the abrading face of the latter against the side of the cutting edge of the blade, as 110 shown in Fig. 2, the greatest pressure being applied to the said disk by the finger 31 when the eccentric is at the high point as illustrated in said figure, and the engagement being for approximately 90 degrees of revolution. During the next 180 degrees of revolution the finger 31' will be thrown into and out of engagement with the disk 14' and cause it to engage with the opposite side of 115 the cutting edge of the blade. 120

The actuating disk 18 is adjustable relatively to the actuating eccentric for the finger rocker 32 whereby different portions of the abrading disks are caused to engage with the blade at will. This is accomplished by setting back or advancing the actuating disk 18 and abrading disks 125 14, 14' relatively to the flange 17 and the rocker actuating eccentric 35 by withdrawing the detent 21 from one of the holes 130

22 and adjusting the disk 18 so that the pin engages in the other hole 22.

It is essential that the abrading disks 14, 14' are only rotatable in one direction as indicated by the arrow in Fig. 2. Should any reverse rotary motion be imparted thereto and a blade engage therebetween, as the disks are forced against said blade by the resilient fingers 31, 31' the disk would be cut by the blade destroying the same. For this purpose I pivotally mount the crank in a bushing 38 projecting laterally from the disk 18 and eccentric to the center thereof with the offset portion of the crank of a length equal to the distance between the center of the actuating disk and the bushing 38. As motion is imparted to the crank handle to rotate the abrading disks in the direction of the arrow 20 the offset portion of the crank will abut against the shoulder 39 projecting beyond the bushing 38. However, should any reverse motion be imparted to the crank the crank will rotate in the bushing 38 until 25 the crank handle is in a position coaxial with the axis of the actuating disk, and in this position will abut against the reverse side of the shoulder 39 preventing reverse rotation of the abrasive disks by 30 the crank.

Variations may be resorted to within the scope of my invention, and portions of the invention may be used without others.

Having thus described my invention, I 35 claim:

1. A device of the class specified, comprising a pair of pliable and rotatable abrasive disks; a fixed blade support projecting between said disks; and means to 40 engage with the outer sides of the disks to cause them to alternately engage with opposite sides of the cutting edge of the blade, substantially as and for the purpose specified.

45 2. A device of the class specified, comprising a pair of pliable and rotatable abrasive disks; a fixed blade support projecting between said disks; and a pusher to engage with and to cause a portion of one abrasive disk to engage with one side of the cutting edge of the blade alternately with the engagement of a portion of the other abrasive carrying member with the opposite side of the cutting edge of the blade, substantially 50 as and for the purpose specified.

55 3. A device of the class specified comprising a pair of abrasive carrying disks; means to rotate said disks; a blade support projecting between and separating said disks; a pusher to engage with and cause a portion of one disk to engage with one side of the cutting edge of the blade alternately with the engagement of a portion of the other disk with the opposite side of the cutting edge of the blade; and means 60

to adjust the rotating means whereby to cause different portions of the disks to engage with the blade, substantially as and for the purpose specified.

4. A device of the class specified, comprising a pair of pliable and rotatable face-butted disks; a blade support projecting between and separating the disks to support the blade in a fixed position; and means to rotate the disks and cause the same to alternately engage with opposite sides of a cutting edge of the blade carried by the support. 70

5. A honing and stropping device for cutting instruments, comprising a pair of pliable and rotatable face-butted disks; a blade support projecting between and separating the disks; means to rotate the disks means actuated by the disk rotating means to bear against and cause the disks to alternately engage with opposite sides of the cutting edge of the blade; said disks and disk rotating means being adjustable relative to said latter means to cause different portions of the disks to engage with 85 the blade. 90

6. A device of the character described comprising a pair of revoluble disks provided with abrasive surfaces, means for supporting a blade between said disks, and 95 mechanism for first applying pressure to each disk to force it toward the blade and then releasing each disk from such pressure.

7. A device of the character described comprising a pair of revoluble disks provided with abrasive surfaces and made of material sufficiently flexible to be indented by pressure, means for supporting a blade between said disks, and a finger for applying pressure to a small portion only of each disk in order to cause said small portion thereof to extend toward the blade. 100 105

8. A device of the class specified, comprising a pair of pliable and rotatable disks; means to rotate the disks a blade support projecting between the disks; and a pair of oscillatory resilient fingers, one located adjacent the outer surface of each disk; and means actuated by the disk rotating means to oscillate said fingers as the disks are rotated to cause said fingers to alternately engage with the outer surface of the disks to cause one disk to engage with one side of the cutting edge of the blade alternately with the engagement of the other disk with 110 the opposite side of the cutting edge of the blade. 115

9. A device of the class specified, comprising a pair of pliable and rotatable disks; a blade support projecting between the disks; a pair of clamping members engaging at opposite sides of the blade to maintain it in its support; and a pair of resilient fingers adjacent the outer surfaces of the disks, said fingers being actuated as the disks 120 125 130

are rotated to alternately engage with the disks whereby one disk engages with one side of the cutting edge of the blade alternately with the engagement of the other disk at the opposite side of the cutting edge of the blade.

10. A device of the class specified, comprising a pair of pliable and rotatable disks; a blade support projecting between the disks; a pair of clamping members engaging at opposite sides of the blade to maintain it in its support; a gage to limit the movement of the blade between the disks and to withdraw said blade from between the disks; and a pair of resilient fingers adjacent the outer surfaces of the disks, said fingers being actuated as the disks are rotated to alternately engage with the disks, whereby one disk engages with one side of the cutting edge of the blade alternately with the engagement of the other disk at the opposite side of the cutting edge of the blade.

11. A device of the class specified, comprising a pair of pliable and rotatable disks; a blade support projecting between said disks; a rocker; a pair of resilient fingers carried by said rocker adjacent the outer surfaces of the disks; said rocker being actuated as the disks are rotated whereby the fingers alternately engage with the outer surfaces of the disks to cause one disk to engage with one side of the cutting edge of the blade alternately with the engagement of the other disk with the opposite side of the cutting edge of the blade.

12. In a device of the class specified, the combination of a pair of pliable and rotatable disks; a blade support projecting between said disks; a rocker; a pair of fingers carried by said rocker adjacent the outer surfaces of the disks; said rocker being actuated as the disks are rotated, whereby the fingers alternately engage with the outer surfaces of the disks to cause one disk to engage with one side of the cutting edge of the blade alternately with the engagement of the other disk with the opposite side of the cutting edge of the blade, comprising an eccentric, a strap surrounding said eccentric, and a link to connect the eccentric strap with the rocker.

13. In a device of the class specified, the combination of a pair of pliable face-butted disks; means to rotatably support said disks, comprising a rotatably mounted bushing passing through a central opening in the disks and having an annular flange to engage the outer side of one of the disks, an annular member rotatably mounted on the bushing at the outer side of the other disk, said member having laterally projecting pins adapted to pass through apertures in the disks with the free ends thereof bearing against the face of the flange on the bushing,

and a crank connected to said annular member; a blade support projecting between the disks; and a pair of resilient fingers adjacent the outer surfaces of the disks to alternately engage with the disks to alternately cause the disks to engage with opposite sides of the cutting edge of the blade.

14. In a device of the class specified, the combination of a pair of pliable disks; means to rotatably support said disks, comprising a rotatably mounted bushing passing through a central opening in the disks and having an annular flange to engage the outer side of the disks, an annular member rotatably mounted on the bushing at the outer side of the other disk, said member having laterally projecting pins adapted to pass through apertures in the disks with the free ends bearing against the face of the flange on the bushing, and a crank connected to said annular member; a blade support projecting between the disks; and a pair of resilient fingers adjacent the outer surfaces of the disks to alternately cause the disks to engage with opposite sides of the cutting edge of the blade.

15. In a device of the class specified, the combination of a base having an upright standard; a stud fixed in said standard; a pair of pliable disks; means to rotatably support said disks, comprising a bushing rotatably mounted on the stud and having an annular flange to engage the outer side of one of the disks, an annular member rotatably mounted on the stud at the outer side of the other disk, said member having laterally projecting pins adapted to pass through apertures in the disks with the free ends bearing against the face of the flange on the bushing, and a crank connected to said annular member; a blade support projecting between the disks; and a pair of resilient fingers adjacent the outer surfaces of the disks to alternately cause the disks to engage with opposite sides of the cutting edge of the blade.

16. In a device of the class specified, the combination of a pair of pliable disks; means to rotatably support said disks, comprising a rotatably mounted bushing passing through a central opening in the disks and having an annular flange to engage the outer side of one of the disks, an annular member rotatably mounted on the bushing at the outer side of the other disk, said member having laterally projecting pins adapted to pass through apertures in the disks with the free ends bearing against the face of the flange on the bushing, and a crank connected to said annular member; a blade support projecting between the disks; a pair of resilient fingers adjacent the outer surfaces of the disks to alternately engage with opposite sides of the cutting edge of the blade.

with the disks to alternately cause the disks to engage with opposite sides of the cutting edge of the blade; and means to adjust the disk rotating means whereby to cause different portions of the disks to engage with the blade.

17. In a device of the class specified, the combination of a pair of pliable disks; means to rotatably support said disks, comprising a rotatably mounted bushing passing through a central opening in the disks and having an annular flange to engage the outer side of one of the disks, an annular member rotatably mounted on the bushing 10 at the outer side of the other disk, said member having laterally projecting pins adapted to pass through apertures in the disks with the free ends bearing against the face of the flange on the bushing, and a crank connect- 15 ed to said annular member; a blade support projecting between the disks; a pair of resilient fingers adjacent the outer surfaces of the disks to alternately engage with the disks to alternately cause the disks to engage 20 with opposite sides of the cutting edge of the blade; and means to adjust the disk rotating means whereby to cause different portions of the disks to engage with the blade, comprising a spring detent carried by the 25 annular member and adapted to engage with either one of a plurality of apertures in the bushing flange.

18. A device of the class specified, comprising a fixed blade support; a pair of face- 35 butted rotatable abrasive disks at opposite sides of said support to be normally out of contact with a blade carried by the support; and means to push against and cause said disks to alternately engage with opposite 40 sides of the cutting edge of the blade.

19. A honing and stropping device for cutting instruments, comprising a pair of rotatable abrasive members each member having two different abrasive surfaces; 45 means to support a cutting instrument between said members in a fixed position; means to engage with and cause the abrasive members to engage with opposite sides of the cutting edge of the cutting instrument; 50 and means to rotatively adjust the abrasive members at will relative to each other to cause the different abrasive portions of said members to engage with the cutting instrument and adapt the same to honing or stropping.

20. A honing and stropping device for cutting instruments, comprising a pair of face-butted rotatable abrasive disks each disk having two different abrasive surfaces 55 on the abutting surfaces thereof; means to

rotate said disks; a fixed support for a cutting instrument to engage between said abrasive disks; means actuated by the abrasive disk rotating means to cause said abrasive disks to alternately engage with opposite sides of the cutting edge of the cutting instrument, and means to adjust the abrasive disks relative to each other to cause the different abrasive surfaces of the abrasive disks to engage with the cutting instrument 65 to adapt the same to honing or stropping.

21. In a device of the class specified, the combination of a pair of rotatable disks; a fixed blade support projecting between said disks; a pair of oscillatory fingers adjacent 75 the outer faces of the disks; an eccentric rotatable with the disks; and flexible means to connect the fingers with the eccentric whereby as the disks and eccentric are rotated the fingers will alternately engage 80 with the outer surfaces of the disks to cause one disk to engage with one side of the cutting edge of the blade alternately with the engagement of the other disk with the opposite side of the cutting edge of the 85 blade.

22. A device of the character described comprising a pair of revoluble disks provided with oppositely disposed faces having abrasive surfaces, said disks being sufficiently flexible to be indented by pressure applied locally to a small portion thereof, so that other portions are left practically undisturbed by said pressure, means for holding a blade between said disks, and means 90 for applying pressure to small areas only of said disks in proximity to the blade, in order to flex said disks and cause portions thereof to extend toward the blade.

23. A device of the character described, 100 comprising a revoluble disk provided with a normally flat face having an abrasive surface, said disks being sufficiently flexible to become indented under pressure applied to a small portion only of said disk, means for supporting a blade adjacent said face, and means for applying pressure upon a small area only of said disk, at points adjacent the position of said blade as said disk revolves.

24. In a sharpening machine, the combination of a pair of flexible disks and a pair of pushers geared so as to alternately and at different periods of time cause contacts to be made between the instrument to be 115 sharpened and said disks.

ALFRED FORNANDER.
